UNITED STATES PATENT OFFICE.

JAMES C. PATTEN, OF KOKOMO, INDIANA, ASSIGNOR TO GLOBE STOVE & RANGE COMPANY, OF KOKOMO, INDIANA.

ELECTRIC HOT-PLATE OR HEATING UNIT.

1,238,807.

Specification of Letters Patent. Patented Sept. 4, 1917.

Application filed October 4, 1915. Serial No. 59,912.

To all whom it may concern:

Be it known that I, JAMES C. PATTEN, a citizen of the United States, residing at Kokomo, county of Howard, State of Indiana, have invented certain new and useful Improvements in Electric Hot-Plates or Heating Units, of which the following is a specification:

This invention relates to improvements 10 in electric hot plates or heating units.

The objects of the invention are:

First, to provide improved means of confining and delivering the radiant heat developed by the resistance coils or heating 15 means to the vessel or cooking utensil placed thereon.

Second, to provide improved means for securing intimate contact of the metallic top plate in such a unit with the flat bottom 20 of a kettle or cooking utensil.

Third, to provide improved means of retaining the heat within such a hot plate and compelling its delivery to the kettle or cooking utensil disposed above.

Fourth, to provide improved means of 25 providing for the avoidance of a disarrangement of parts due to the expansion of the metal top plate.

Further objects, and objects relating to 30 details and economies of construction and operation, will definitely appear from the detailed description to follow.

I accomplish the objects of my invention by the devices and means described in the 35 following specification. The invention is clearly defined and pointed out in the claims.

A structure constituting a preferred embodiment of my invention is illustrated in 40 the accompanying drawing forming a part of this specification, in which:

Figure I is a top plan view of a hot plate or unit embodying the features of my invention.

Fig. II is a transverse detail sectional elevation view taken on a line corresponding to line 2—2 of Fig I.

Fig. III is a detail inverted plan view of the hot plate as illustrated in Fig. I.

In the drawing similar reference characters refer to similar parts throughout the several views, and the sectional views are taken looking in the direction of the little arrows at the ends of the section lines.

Considering the numbered parts of the

drawing, my improved hot plate is intended for use in a top plate or structure and the same comprises a cup shape bottom metallic piece 1, within which is an asbestos lining 2 which surrounds a porcelain or other non-conductor plate 3. A metallic top plate 4 is provided which is secured in place by bolts 5 disposed through apertures 6 through the parts above enumerated. An outer groove 7 is formed in the upper face of the porcelain plate 3, having preferably polished walls. Within the bottoms of these grooves are disposed heating coils. Coils 8 are in the outer grooves and are connected at their terminals to suitable binding posts 9 and 10.

A second coil 11 is disposed in grooves 12, 13 which is looped back and forth in substantially parallel relation at the central portion of the plate in elongated loops and 75 provided with a portion extending substantially parallel to the outer peripheral groove 7 at each side.

The terminal 15 is connected to the binding post 14 and the terminal 16 is connected 80 to binding post 10. It will thus be seen that the central portion of the heating coil is made up of portions disposed in substantially parallel relation. The outer coil is preferably of greater resistance. The coils 85 are effectively retained in position in the bottom of the grooves and attaching devices may be provided where found necessary, consisting of little cotter pins or other means; or the coils may be cemented in 90 place.

The top plate 4 has a comparatively broad unperforated peripheral flange which is cast with slots 18, 18 on opposite sides thereof and toward the side of the elongated groove in the plate at the center. A series of segmental slots 19, 20, 21, 22 extend substantially around the plate except for the connecting supports 23 opposite the ends of the grooves at the center, and the 95 connections 24 and 25 at each side in proximity to the open slots 18 and symmetrically opposite therefrom. The part 23 extends well in at 27 and the part 26 extends well in at the opposite side, forming a sort 100 of end to the central grid.

Segments of metal are disposed between the slots at 28, 29 toward the outside, and at 30, 31 just within the same and 32, 33, 34, 35, and 36 are in parallel relation at the 110

center forming elongated slots corresponding to the grooves in the insulator plate beneath. On the opposite sides of each of the slots as formed extend little guard fingers 5 37 which prevent any article, such as a spoon, a knife, or a fork, from being dropped down into contact with the resistance heating coils and thus grounding the same.

The purpose of this arrangement has 10 been explained and is also specifically described in the application of Louth and Jackson, Ser. No. 42,403, filed July 28, 1915.

In this invention the slotting for the screws is avoided by disposing one of the 15 same within the plate at 26 and screws at each side in the connecting segments 30, 31, so that there are three points of engagement in portions of the plate so disposed that they are not subjected to the highest 20 expansion. This permits the metallic plate to remain evenly in place over the insulator plate, and the peculiar slotting and the radial slots at 18, 18 permit the expansion to occur without material disarrangement 25 of the plate in its relation to the insulator plate beneath.

The general contour of the upper face of the plate 4 is concave, as indicated at 17, so that the flat bottom of a kettle or vessel 30 4' placed thereon would contact at the periphery, thus effectively retaining any heat within by confining the same at these points. Most vessels having sheet metal bottoms are a little convexed and this depression causes them to fit into close contact with the heated metal of the top plate. The central heating of the same has a still further tendency to convex the same downwardly and the concave formation of the 40 plate thus insures the most effective contact of the sheet metal bottom of a kettle or cooking utensil, thereby enhancing the delivery of heat through the walls thereof to the contents of the same. This is of very 45 considerable advantage, as it utilizes to the fullest extent the heat developed by the electric current in the resistance coils.

The plate 4 projecting like a peripheral flange enables this heat unit to be used in 50 a top plate, something after the fashion of a stove lid in the opening of a stove top.

I have not shown the connections for delivering the current hereto. The concaved metal top plate can be effectively made use 55 of in other relations and the other features would be quite effective with a flat top plate like that referred to in the application above mentioned. The whole structure, however, is highly effective in the specific 60 form in which it appears. The sheet metal container 1 protects the same against injury. The insulation, both of asbestos and the porcelain plate, retain the heat developed by the resistance coils and cause the

same to be delivered upwardly. The particular form of top plate insures the effective delivery thereof.

From what I have stated, it is clear that the structure can be considerably modified without departing from my invention. I, however, believe that the specific structure possesses a high degree of merit and I desire to claim the same in its specific form as well as broad as indicated in the appended claims.

Having thus described my invention, what I claim as new and desire to secure by Letters Patent is:

1. In an electric heat unit, the combination of an insulator plate with suitable grooves in the upper face thereof, a heating coil means disposed in the said grooves, a metallic top shield plate disposed over the insulator plate, slotted to expose the coils and concave at the center on its upper surface to conform to the convexity of any vessel thereon, an asbestos packing around the said insulator plate, a metal bottom shield around the bottom of said packing, a plurality of screws disposed through the 85 said top plate and insulator means and bottom metal shield, coacting for the purpose specified.

2. In an electric heat unit, the combination of an insulator plate with suitable grooves in the upper face thereof, a heating coil means disposed in the said grooves, a metallic top shield plate disposed over the insulator plate, slotted to expose the coils and concave at the center on its upper surface to conform to the convexity of any vessel placed thereon, an asbestos packing around the said insulator plate, a plurality of screws disposed through the said top plate and insulator means, coacting for the purpose specified.

3. In an electric heat unit, the combination of an insulator plate with suitable grooves in the upper face thereof, a heating coil means disposed in the said grooves, a metallic top shield plate disposed over the insulator plate, slotted to expose the coils and concave at the center on its upper surface to conform to the convexity of any vessel placed thereon, a plurality of screws disposed through the said top plate and insulator means, coacting for the purpose specified.

4. In an electric heat unit, the combination of an insulator plate with suitable grooves in the upper face thereof, a heating coil means disposed in the said grooves, a metallic top shield plate disposed over the insulator plate, slotted to expose the coils, an asbestos packing around the said insulator plate, a metal bottom shield around the bottom of said packing, a plurality of screws disposed through the said top plate

and insulator means and bottom metal shield, coacting for the purpose specified.

5. In an electric heat unit, the combination of an insulator plate with suitable 5 grooves in the upper face thereof, a heating coil means disposed in the said grooves, a metallic top shield plate disposed over the insulator plate, slotted to expose the coils, an asbestos packing around the said insu- 10 lator plate, a plurality of screws disposed through the said top plate and insulator means, coacting for the purpose specified.

6. In an electric heat unit, the combination of an insulator plate with suitable 15 grooves in the upper face thereof, a heating coil means disposed in the said grooves, a metallic top shield plate disposed over the insulator plate, slotted to expose the coils, a plurality of screws disposed through the 20 said top plate and insulator means, coacting for the purpose specified.

7. In an electric heat unit, the combination of an insulator plate with suitable 25 grooves in the upper face thereof, a heating coil means disposed in the said grooves, a metallic top shield plate disposed over the insulator plate, slotted to expose the coils and concave at the center on its upper sur- 30 face to conform to the convexity of any ves- sel thereon, coacting for the purpose speci- fied.

8. In an electric heat unit, the combina-

tion of an insulator plate with suitable 35 grooves in the upper face thereof, a heating coil means disposed in the said grooves, a metallic top shield plate disposed over the insulator plate and concave at the center on its upper surface to conform to the convexity of any vessel thereon, coacting for the purpose specified.

40 9. In an electric heat unit, the combination with suitable electric heating means and a top shield plate therefor concaved on its upper surface, of a flat bottomed vessel contacting with the outer upper surface of 45 said top plate.

10. In an electric heat unit, the combination of suitable electric heating means and a top shield plate therefor concaved on its 50 upper surface with a peripheral flange, the interior slotted into protecting bars, and the peripheral flange slotted radially to compensate for expansion, as specified.

11. The combination of a heater having a concave upper surface and a flat bottomed vessel supported on the outer upper part of 55 said surface.

In witness whereof, I have hereunto set my hand and seal in the presence of two witnesses.
